SEWING BOX

Dominic A. De Santis, Scottdale, Pa.

Application August 26, 1955, Serial No. 37,673

Term of patent 7 years

(Cl. D3—19)

Fig. 1

FIG. 2

Figure 1 on the drawing is a front perspective view of a sewing box showing my new design as it appears with the drawer thereof in partially opened position, and

Figure 2 is a rear elevational view of the sewing box shown in Figure 1 with parts thereof being shown broken away to illustrate the double walls.

I claim:

The ornamental design for a sewing box, substantially as shown.
